UNITED STATES PATENT OFFICE.

ELMER E. WINTERSGILL, OF GULFPORT, FLORIDA.

SUCTION-DREDGE SHELL-SCREEN.

1,263,829.

Specification of Letters Patent. Patented Apr. 23, 1918.

Application filed July 23, 1917. Serial No. 182,332.

To all whom it may concern:

Be it known that I, ELMER E. WINTERSGILL, a citizen of the United States of America, residing at Gulfport, in the county 5 of Pinellas and State of Florida, have invented certain new and useful Improvements in Suction-Dredge Shell-Screens, of which the following is a specification, reference being had therein to the accompanying 10 drawing.

This invention relates to a suction dredge shell screen and has for its object the production of a simple and efficient screen which may be kept clean of all foreign 15 substance.

Another object of this invention is the production of a simple and efficient screen which will easily and efficiently separate the shell when dredged from the sand, grass, 20 and water.

With these and other objects in view this invention consists of certain novel combinations and arrangements of parts, as will be hereinafter fully described and claimed.

25 In the accompanying drawings:

Figure 1 is a front elevation of the dredge screen.

Fig. 2 is a section taken on line 2—2' of Fig. 1.

30 Fig. 3 is a side elevation of the dredge screen in an operative position.

Fig. 4 is a vertical section taken through the bottom end of the dredge screen showing the cutting knife in operation.

35 Fig. 5 is a perspective view of a modified form of the invention, wherein the suction dredge shell screen is semi-circular in cross section.

Fig. 6 is a transverse section taken on 40 line 6—6 of Fig. 5, looking in the direction of the arrow.

By referring to the drawings it will be seen that 1 designates the discharged nozzle which is adapted to discharge the material 45 dredged directly against the screen, as shown clearly in Fig. 3 of the drawings. A plurality of supporting bars or beams 2 are employed, and these beams 2 engage the respective ends of the top and bottom plates 3 and 4 of the screen. The screen is provided with a plurality of side rails 5 which rails are firmly held in engagement with the top and bottom plates 3 and 4 by means of the nuts 6, shown in Fig. 1 of the drawings.

55 The upper and lower plates 3 and 4 are provided with a plurality of sockets 6 formed

upon their inner faces which sockets 6 receive the reduced ends 7 of the screen bars 8. The screen bars 8 are preferably circular in cross section and are firmly held 60 between the upper and lower plates 3 and 4 by means of the nuts 6 which are threaded upon the respective ends of the end rails 5. A cutting knife 9 is carried by the top plate 3 upon the outer face of the screen and a 65 cutting knife 10 is carried by the bottom plate 4 as shown clearly in Figs. 1 and 2 of the drawings.

A cleaner bar 11 is slidably mounted upon the bars 8 and is provided with a plurality 70 of apertures 12 through which the bars 8 extend. It should be understood that as the cleaner bar 11 is moved longitudinally of the screen, these bars will be scraped by means of the cleaning bar and the reciprocating movement thereof upon the bars.

A plurality of elongated rods 12 are connected to the cleaner bar 11 by means of the collars 13 shown in Fig. 1, and the upper ends of these rods 12 are connected together 75 by means of a transversely extending plate 14. The plate 14 carries an eye 15 which is connected to any suitable or desired lifting means 17 for the purpose of raising and lowering the rods 12. The lower ends of 80 these rods 12 pass through suitable apertures 18 formed in the bottom plate 4, and it will be seen that as the cleaner bar 11 travels longitudinally of the rods or bars 8, no additional opening will be produced 85 throughout the entire width of the screen. It should be understood that should grass or the like accumulate upon the screen and between the bars 8, the cleaner bar 11 will

cause the grass or other foreign matter to 90 be cut between the bar 11 and the edge of the cutting knives 9 and 10. Special attention is invited to Fig. 4 in connection with the above statement. It, of course, should be understood that the flow of the water 100 through the section will wash the accumulated grass from the face of the screen after the same has been cut upon the knives 9 and 10. It should be understood that if it is so desired the bars or rods 12 may be raised 105 by means of a cable or the like and may be allowed to drop through gravity for the reason that the same may be made of suitable weight to accomplish the desired purpose.

110 From the foregoing description it will be seen that a very simple and efficient device

has been produced for conveniently supporting the shell when dredged from the sand, grass and water, and that owing to the construction of the knives 9 and 10, the grass will be prevented from being entangled upon the rods 8.

By carefully considering Figs. 5 and 6, it will be seen that a modified form of the invention is disclosed, wherein the screen is arranged on the arc of a circle, upon its transverse axis, and comprising an outer frame 19 having end plates 20, between which plates are arranged screen bars 21. A cutting knife 22 is carried at each end of the suction dredge shell screen and a cleaning bar 23 is slidably mounted upon the screen bars 21, as shown in Fig. 5. This cleaner bar is engaged by means of elongated rods 24, which elongated rods 24 engage at their upper ends a transversely extending connecting bar 25. The lower ends of these bars 24 work through the apertures 26 formed in the lower end plates 20. It will be seen from the foregoing description, that the screen bars 21 may be kept clean by reciprocating the cleaning bar 23 upon the screen bars 21 and bringing the same into engagement with the cutting knives 22.

What is claimed is:

- 30 1. A dredge shell screen comprising a frame, said frame comprising a plurality of vertical extending bars, a cleaner bar, said vertical extending bars passing through said cleaner bar, cutter plates carried by said frame and fitting in close engagement upon said vertical extending bars, and rods connected to said cleaner bar for forcing the same into engagement with said cutter plates for cutting any entangling of foreign substance collecting thereon.

2. A dredge shell screen comprising a frame, a plurality of vertical extending bars, a cleaner bar, a plurality of cutter plates carried by said frame and adapted to be engaged by said cleaning bar for cutting material accumulating between said cutter plates and said cleaning bar, a plurality of operating rods working vertically through said frame, a tie-plate engaging the upper ends of said operating bars and connecting the same together, the lower ends of said last mentioned bars extending vertically through said frame and constituting a guide for the bottom end of said operating bars, and means carried by said tie-plate for facilitating the attachment of operating means thereto.

3. A dredge shell screen comprising a frame, said frame comprising end bars, said end bars being covered on the arc of a circle, cutting plates carried by said frame, screen bars carried by said end plates, a cleaning bar working upon said screen bars and adapted to reciprocate through said screen bars arranged upon said end plates upon the arc of a circle and said cleaning bar adapted to be forced into engagement with said cutting plates for cutting material accumulating upon said screen bars.

4. A dredge shell screen comprising a frame, cutting plates secured to said frame, a cleaner bar reciprocately mounted upon said frame and adapted to force material accumulating upon said screen down upon said cutting plates for cutting material accumulating upon said screen free from said screen.

In testimony whereof I hereunto affix my signature.

ELMER E. WINTERSGILL.
